UNITED STATES PATENT OFFICE.

CHARLES B. RODGERS, OF BORDENTOWN, NEW JERSEY.

CONDUIT-THREADER.

No. 797,457.

Specification of Letters Patent.

Patented Aug. 15, 1905.

Application filed March 25, 1904. Serial No. 199,966.

To all whom it may concern:

Be it known that I, CHARLES B. RODGERS, a citizen of the United States, residing at Bordentown, in the county of Burlington and State of New Jersey, have invented a new and useful Conduit-Threader, of which the following is a specification.

My invention relates to conduit-threaders designed especially for threading or feeding electric wires, cables, or the like through underground conduits and for removing obstructing accumulations from sewers or other mains, and has for its object to produce a comparatively simple inexpensive device of this character which in practice will efficiently perform its function and one which may be readily removed from the conduit after traveling partially through the latter.

To these ends the invention comprises the novel features of construction and combination of parts more fully hereinafter described.

In the accompanying drawings, Figure 1 is a longitudinal section of a conduit, illustrating my improved device operating therein. Fig. 2 is a detail top plan view of a portion of the device removed. Fig. 3 is a side sectional elevation, on an enlarged scale, of a portion of the rear section of the device. Fig. 4 is a similar view of a portion of the forward section of the device. Fig. 5 is a detail sectional plan, on an enlarged scale, of a portion of the device at the juncture of the sections. Fig. 6 is a vertical sectional elevation on the line 6 6 of Fig. 3 as viewed in the direction of the arrow. Fig. 7 is a vertical sectional elevation on the line 7 7 of Fig. 4 viewed in the direction of the arrow.

Referring to the drawings, it will be seen that the body portion of the device comprises a forward primary tubular section 1 of circular form in cross-section and a rear secondary solid section 2 of square or other non-circular form in cross-section, said sections being connected by a universal joint 3 and the rear section provided adjacent to its longitudinal center with a universal joint 4, whereby the device may readily follow the course of curved conduits.

The primary section 1, which carries at its forward end a substantially arrow-shaped grappling member 5, is provided between its ends with a pair of primary longitudinally-disposed slots or guideways 6, arranged in spaced parallel relation one in advance of the other and extending wholly through the section transversely, and with a pair of secondary

slots or guideways 7, situated, respectively, adjacent to the forward ends of the primary slots 6 and disposed diametrically at right angles to the latter, the secondary slots being arranged longitudinally of the section and extended wholly through the latter transversely.

Seated, respectively, in the guide-slots 6 are bearings or expander members 8, each comprising a pair of rearwardly-convergent plates or sections 9, provided upon their side edges with laterally-outstanding guide-flanges 10, said plates 9 being pivoted adjacent to their rear ends, for their forward ends to swing toward and from each other in a direction transversely of the body, by means of pintles 11, which also serve to fix the members 8 against movement longitudinally of the section 1, said pintles terminating upon one side of the section in perforated heads constituting guide openings or eyes 12, arranged in alignment with and somewhat in rear of the secondary slots 7. The sections 9 of the members 8 are connected adjacent to their forward ends by means of toggle-links 13, the central pivoting-pintles 14 of which engage the guide-slots 7 and terminate upon one side of the section in perforated heads 15, which receive and are fixed to an operating rod or element 16, adapted for longitudinal reciprocation and mounted in the guide-openings 12, there being mounted upon the rod between the foremost guide 12 and the rearmost head 15 a normally expanded spring 17, which bears at its ends upon said parts and serves to exert rearward pressure upon the rod 16 for maintaining the same in normal position.

Fixed upon the rear end of the section 1 is a head-plate 18, having a pair of oppositely-disposed openings 18', through one of which the rod 16 passes, there being fixed upon the rear end of the rod a bearing member or plate 19, having a central opening 20 for the reception of the rear section 2 of the body, and a forwardly-projecting guide arm or rod 21, adapted to work in the other of said openings 18'. Attached to the head 18 is a suitable casing 22 for the reception of a pulley 23, around which is passed an operating rope or cable 24, the flights of which pass rearward through oppositely-disposed openings 25, provided in the head.

Engaged with the guide-flanges 10 of the members 8 are engaging members or fingers 26, provided upon the front ends of supporting arms or members 27, disposed in pairs arranged, respectively, upon the opposite outer

edges of the bearing members 8, longitudinally of which latter they extend, the rear ends of the arms being angularly bent inward and pivotally connected in rear of the members 8 and adapted for movement longitudinally of the primary guide-slots 6, while the forward ends of the arms are bifurcated to produce bearings in which are pivoted anti-friction balls or rollers 28, adapted in practice to travel, respectively, upon the outer inclined edges of the sections 9. The arms 27, which together with the rollers 28 constitute feeding devices for feeding the threader through the conduit, are adapted for longitudinal movement within the guides 6, but are normally pressed forward therein and into contact with the relatively fixed members 8 by means of normally expanded springs 29, housed within the tubular section and bearing at their rear ends upon pins or other suitable stops 30. Attention is directed to the fact that as the feeding devices move rearward in the manner hereinafter explained the spring 29 will be compressed, while at the same time the forward ends of the arms 27 will be drawn inward toward each other, owing to engagement of the fingers 26 with the inclined guide-flanges 10 for the purpose which will herein-after appear.

Mounted for longitudinal movement or reciprocation upon the rear section 2 of the body is a non-rotary sleeve 31 of suitable length, provided upon its rear end with a fixed head 32, having attached thereto a casting 33, in which is journaled a pulley 34, having passed therearound an operating rope or cable 35, the flights of which extend rearward through guide-openings 36, provided in the head 32, and corresponding guide-openings 37, formed through a head-plate 38, fixed upon the rear end of the section 2. The sleeve 31 has fixed thereon in longitudinal spaced relation a pair of bearing members 39, each composed of a pair of forwardly-divergent sections 40, bearing upon their outer edges guide-flanges 41, adapted for engagement by inturned fingers 42, carried at the forward ends of forwardly-divergent supporting-arms 42', which sustain at their forward ends pivoted anti-friction-rollers 43 and are pivotally connected at their rear ends to suitable connecting members or collars 44, adapted for sliding movement longitudinally of the sleeve 31, whereby rearward movement of the collars will cause an inward movement of the forward ends of the arms 42 toward each other in the manner described in connection with the arms 27. The collars 44 are normally pressed forward to bear upon the rear ends of the members 39 by means of normally expanded springs 45, the rear ends of which bear upon bearing rings or collars 46, adapted for adjustment longitudinally of the sleeve and to be fixed in position thereon by suitable set-screws, there being formed

upon the rings or collars 46 at one side of the section guide openings or eyes 47, through which is threaded one flight of the primary operating rope or cable 24, the terminal of the other flight of which extends through and is knotted in rear of a perforated head 48, cast or otherwise fixedly associated with the forward bearing member 39, while the terminal of one flight of the other operating-rope 35 is knotted in rear of the head 32, whereby rearward traction upon the primary operating-rope 24 will serve to move the sleeve or carrier 31, together with the mechanism carried thereby, forward upon the section 2 and traction upon the secondary operating-table 35 will move the carrier rearward for the purpose which will be described later.

Provided on the members 39 and in alignment upon one side of the carrier 31 is a pair of perforated guides 49, adapted to receive a longitudinally-movable operating rod or element 50, having fixed thereon and movable therewith bearing-collars 51, which encircle the sleeve 31, respectively, in advance of the connecting members or collars 44, whereby rearward movement of the rod 50 will impart a similar movement to the supporting-arms 42, which conjointly with the rollers 43 constitute secondary feeding devices, the rearward movement of said devices being against the action of the springs 45.

In practice when the threading device is inserted in a conduit the primary feeding devices carried by the section 1 will be initially contracted transversely to conform to the diameter of the conduit caused by rearward movement of the supporting-arms 27 against the action of the adjacent springs, which latter in tending to expand force the rollers 28 into secure frictional engagement with the inner wall of the conduit, a similar action occurring in connection with the secondary feeding devices carried by the section 2 upon the entrance of the latter into the conduit. The apparatus having been entered into the pipe and supposing the carrier 31 to be in its forward position upon the section 2, traction upon the operating-rope 35 will tend to draw the carrier and its feeding devices rearward upon the section 2, which action, owing to the secondary devices being in engagement with the conduit-walls, will project the front section 1 forward until the head 38 comes in contact with the head 32, the forward movement of the section 1 being permitted by the primary engaging devices yielding through the medium of the springs. Traction upon the primary operating-rope 24 will then move the carrier 31 forward upon the section 2, the primary engaging devices being in the meantime in engagement with the walls of the conduit and the secondary engaging devices yielding, as before explained, to permit said movement. If it be desired to withdraw the apparatus from the pipe, continued traction

upon the rope 24 will, owing to the forward end of the operating-rod 50 bearing on the plate 19, effect a rearward movement of the operating-rod 50 and at the same time a forward movement of the rod 16, whereby the secondary feeding devices will be moved rearward, and thus contracted, while at the same time the toggle-links 13 will be acted upon for moving the forward ends of the sections 9 inward toward each other, thus contracting the primary feeding devices and permitting the apparatus as a whole to be readily removed from the conduit. It is apparent that owing to this construction the device may be fed forward in a conduit until the grappling member 5 engages an obstruction in the latter and be then readily withdrawn for removing the obstruction, it being understood, of course, that where the device is employed for threading wires or the like through the conduits the said wires will be attached to the ends of the operating-ropes.

Having thus described the invention, what I claim is—

1. In a device of the class described, a sleeve or tube having slots formed in the top, bottom and sides thereof, oppositely-disposed bearing members extending into the top and bottom slots and connected within the tube by a pivotal pin extending through the side walls of the latter and provided with perforated heads at its outer ends, toggles connecting the forward ends of the bearing members and extending through the slots into the sleeve, a pivotal pin connecting the inner ends of said toggles and extending through the slots in the sides of the sleeve, and a spring-actuated rod guided in the perforated heads of the pivotal pin of the bearing members and connected with the pivotal pin of the toggles to expand the latter.

2. In a device of the class described, a slotted tubular sleeve, bearing members pivotally engaging the same, pivotally-connected links or toggles connecting the free ends of the bearing members, spring-actuated means engaging the toggles to keep the bearing members normally expanded, pivotally-connected roller-carrying arms engaging the bearing members and partaking of the movement of the latter, and springs engaging said pivotally-connecting arms to keep them normally expanded.

3. In a device of the class described, a slotted tubular sleeve, bearing members extending through the slots in the sleeve and connected pivotally with each other and with the said sleeve, said bearing members being provided with flanges at their outer edges, toggles connecting the free ends of the bearing members,

pivotaly-connected arms movable independently of the sleeve and having roller-carrying ends engaging the flanges of the bearing members, springs bearing against the roller-carrying arms to assist in keeping said arms normally expanded, and means for manipulating the toggles to collapse the free ends of the bearing members.

4. In a device of the class described, the combination of a tubular body, normally inclined bearing members having flanges at their outer edges, longitudinally-movable pivoted spring-actuated arms engaging the flanges of said bearing members and guided thereby, engaging rollers carried by said arms, springs actuating the latter to cause the rollers to travel outwardly upon the bearing members, and means for actuating said roller-carrying arms against the tension of the springs to collapse the roller-carrying ends of said arms.

5. In a device of the class described, a slotted tubular body, collapsible bearing members connected pivotally therewith and having flanged edges, pivotally-connected longitudinally-movable roller-carrying arms engaging the flanged portions of the bearing members, spring means to keep the bearing members and the roller-carrying arms normally expanded, and means for collapsing said bearing members and roller-carrying arms against the tension of the springs.

6. In a device of the class described, a tubular member or body, spring-actuated normally expanded conduit-engaging members connected pivotally with each other within said body and capable of longitudinal movement with relation to the latter, means for collapsing said conduit-engaging members against the tension of the actuating-springs, a non-circular rod connected hingedly with the tubular body and having a universal joint formed therein, a sleeve slidably connected with said non-circular rod, expansible conduit-engaging members connected with said sleeve, springs to keep said conduit-engaging members normally expanded, means for collapsing said conduit-engaging members against the tension of the springs, and means for exerting draft in a forward direction upon the body and upon the sleeve when the conduit-engaging members of said body or sleeve are collapsed.

In testimony that I claim the foregoing as my own I have hereto affixed my signature in the presence of two witnesses.

CHARLES B. RODGERS.
